UNITED STATES PATENT OFFICE.

ANDREW BERT ANDERSON, OF DES MOINES, IOWA, ASSIGNOR OF ONE-HALF TO JEFFERSON SANDUSKY, OF DES MOINES, IOWA.

DOUBLE SAW SET.

Application filed December 20, 1923. Serial No. 681,752.

To all whom it may concern:

Be it known that I, ANDREW BERT ANDERSON, a citizen of the United States of America, and resident of Des Moines, Polk County, Iowa, have invented a new and useful Double Saw Set, of which the following is a specification.

The object of this invention is to provide an improved double saw set wherein means is provided for operating upon two adjacent 10 teeth of a saw simultaneously and setting them in opposite directions relative to the plane of the saw blade.

A further object of this invention is to 15 provide means for simultaneously and with a single operation causing the advance of two spaced plungers of a double saw set.

A further object of this invention is to 20 provide improved means for adjusting one of the plungers and its anvil laterally to adapt the device for operation upon saws having varying spacing of its teeth.

A further object of this invention is to 25 provide improved means for adjusting the plungers and their anvils longitudinally to adapt the device for operation upon saws of varying thickness.

A further object of this invention is to 30 provide improved means for advancing and retracting the plungers.

With these and other objects in view, my invention consists in the construction, arrangement and combination of elements hereinafter set forth, pointed out in my 35 claims and illustrated by the accompanying drawing, in which—

Figure 1 is a side elevation of my improved double saw set, the handles being broken away to economize space. Figure 2 is a plan of the same. Figure 3 is a longitudinal section on the line 3—3 of Figure 2. Figure 4 is a cross-section on the line 4—4 of Figure 3. Figure 5 is a longitudinal detail section on the line 5—5 of Figure 4. Figure 6 is a cross-section on the line 6—6 of Figure 3.

In the construction of the device as shown a frame or housing is provided which is substantially rectangular in plan view and in side elevation, and also in cross-section throughout the major portion of its length. The frame or housing is composed of a top 10, side walls 11, 12 and end walls 13, 14, and is open at its bottom but closable by a

removable bottom or floor member 15 55 adapted to be secured in place by screws 16 seated in margins of the side and the forward end wall. A rigid or stationary handle 17 is formed on and projects downwardly from the rear portions of the side walls 11, 12 and rear end wall 14, and is suitably shaped to fit the hand of an operator. The handle 17 is substantially U-shaped throughout the greater portion of its length and a movable handle or lever 18 (which also may 60 be U-shaped in cross-section) is received within the upper portion of said rigid handle and pivoted thereto, between its ends, by means of a rivet or pin 19. The lever 18 normally is pressed yieldingly away from the handle 17 by means of an expansive coil spring 20 mounted between said members near the fulcrum 19. Rollers 21, 22 are mounted in and transversely of the frame or housing and are spaced apart, in the 70 same horizontal plane. The rollers 21, 22 are formed at their ends with trunnions journaled in vertical grooves 23, 24 respectively, formed in the side walls 11, 12; the grooves 23 relating to the roller 21 opening 75 downwardly to the lower margins of the side walls 11, 12 and normally closed by the bottom plate or floor 15, and the grooves 24 relating to the roller 22 opening upwardly to the upper margins of said side walls and 80 communicating with an aperture 25 formed in the forward portion of the top 10. The rollers 21, 22 are placed in position by sliding their trunnions to the ends of the respective grooves and are held in such position by means of screws 26 mounted through the side walls and seated in the ends of the trunnions. An arm 27 is formed on or rigidly fixed to the roller 21 and extends rearwardly and downwardly therefrom, 85 within the frame or housing. An arm 28 is formed on or fixed to the forward portion of the foremost roller 22, extends upwardly therefrom through the aperture 25 in the top of the frame, turns substantially at right angles and extends rearwardly above the top 10 of said frame and normally in a plane substantially parallel therewith, terminating at a point above the rear end of the arm 27. The upper end of the handle 17 is flexibly connected to the rear ends of the arms 27, 28 respectively by means of links or toggles 29, 30, conjunctively piv-

oted to said handle lever by a pin or rivet 31. The pin 31 lines in a horizontal plane substantially midway between the planes of the pivotal connections of the links or toggles 29, 30 to the arms 27, 28 and is spaced rearwardly therefrom, so that when the handle lever 18, in its lower portion, is moved manually toward the rigid handle 17, by pressure in the hand of an operator 10 against the action of the spring 20, the rear ends of the arms 27, 28 are moved apart in vertical planes, thus causing a rotary oscillation or rocking movement of the rollers 21, 22 in opposite directions, on their axes, said 15 rollers rocking away from each other. The top 10 is formed with an aperture 32 near its rear end through which the link or toggle 30 extends freely. The arm 28 is bifurcated in its forward portion, through which bifurcation the operator can view the space 20 midway between the rollers 21, 22, a central aperture 33 being formed in the top 10 in registry with said bifurcation and above such space. The side walls 11, 12 are formed 25 with tapering notches 34 opening to their lower margins, midway of the space between the rollers 21, 22, and the bottom plate or floor 15 is cut away between the lower edges 30 of said notches, whereby said bottom plate 35 or floor is divided into two separate spaced members, thus providing a space transversely of the frame or housing and extending upwardly from its bottom a material distance, within which a saw blade 35 (dotted lines Figure 3) may project in vertical position, in a common manner, for treatment by the tool.

A block 36 is mounted within the forward end portion of the frame or housing, 40 extending from top to bottom and from side to side thereof, and said block is slidably longitudinally of said frame or housing in seats 37 formed in the top and bottom thereof. A lug 38 is formed on and centrally of 45 and projects forwardly from the block 36 and is received within a cam notch 39 formed in the rearward face of the roller 22, said cam notch being of greater length than the width of said lug. A carrying 50 block 40 is provided at the rear face of the block 36 and is slidably adjustable laterally therein by means of tongue and groove connections 41 (Figure 5). The lateral adjustment of the carrying block 40 in the block 36 is effected and controlled by means of a 55 screw 42 extending loosely through the side wall 11, swiveled in an ear 43 carried by the block 36, and having screw connections with said block 40. An anvil 44 is carried 60 by and vertically adjustable on the carrying block 40, being formed with a tongue sliding in a groove 45 in said block 40. The vertical adjustment of the anvil 44 in the carrying block 40 is effected and controlled 65 by means of a screw 46 swiveled in an ear

47 formed on said block and having screw connections with the lower portion of said anvil, and when so adjusted the anvil is set and locked in place by means of a clamping screw 48 extending loosely through the side 70 wall 11, threaded in the side of the block 40 and adapted to engage at its inner end the tongue of said anvil. A plunger 49 also is carried by the block 36, at one side of the carrying block 40 and anvil 44, and said 75 plunger is formed with a stem 50 (dotted lines Figures 3 and 4) projecting within an aperture in the rear face of said block; and the forward end of said plunger is extended within a rectangular seat 51 in the face 80 of said block, to prevent torsional movement of the plunger.

A second operating block 52 is mounted within the frame or housing, in opposition to the block 36 and on the opposite side of 85 the notches 34 therefrom, and also extends from top to bottom of the housing and from side to side thereof, and said block is slideable longitudinally of said frame or housing 90 in seats 53 formed in the top and bottom thereof. A lug 54 is formed on and centrally of and projects rearwardly from the block 52 and is received within a cam notch 55 formed in the forward face of the roller 21. An anvil 56 is carried by the forward face 95 of the block 52, at one side of the center thereof, said anvil being vertically adjustable by means of a tongue thereon slideable in a groove 57 in said block. Vertical adjustment of the anvil 56 relative to the block 100 52 is effected and controlled by means of a screw 58 swiveled in an ear 59 formed on said block and having screw connections with the bottom of said anvil; and said anvil is set and locked in its adjusted position 105 by means of a clamping screw 60 extending loosely through the side wall 12, threaded through one side of the block 52 and adapted to engage at its inner end the tongue of the anvil. The screws 42, 48 and 60 extend 110 loosely through slots such as 61 (Figure 1) formed in and longitudinally of the side walls of the housing. A plunger 62 also is carried by the forward face of the block 52, 115 at one side of the anvil 56 and said plunger is slidably mounted in a transverse groove or opening 63 in said block and thus adjustable laterally of the device. Lateral adjustment of the plunger 62 in the block 52 is effected 120 and controlled by a screw 64 extending loosely through a slot such as 61 in the side wall 11, swiveled in that portion of the block 52 between one of its ends and the adjacent end of the slot or groove 63, and having screw connections with the said plunger. 125

In practical use the tool is employed in a manner common and well known in setting the teeth of saws, with this difference, that two adjacent teeth of the saw are simultaneously set or bent laterally, in opposite direc- 130

tions, by each operation of the device through manipulation of the lever 18 manually, the position of the saw 34 and two such adjacent teeth being indicated by dotted lines in Figure 3. The operation is effected by pressure of the hand of the operator to contract the lever 18 toward the handle 17, against the spring 20, which spring acts to return the lever, and other members connected therewith, after pressure is relaxed. This oscillation of the lever under manual pressure serves to move and spread the links or toggles 29, 30, oscillate the arms 27, 28 and rock the rollers 21, 22, in opposite directions and away from each other. Such movement of the rollers 21, 22, through the cam grooves or notches 55 and 39 thereof, presses the operating blocks 36 and 52 toward each other by pressure against the ends of the lugs 38 and 54, said blocks sliding in the seats in the frame. Such reciprocation of the blocks 36, 52 carries forward the plungers 49 and 62 and the anvils 44 and 56; the plunger 49 being located opposite to and cooperating with the anvil 56 and the plunger 62 being located opposite to and cooperating with the anvil 44. The plungers 49, 62, as is common, are formed with relatively narrow, vertically extending setting edges, which slope from top to bottom, and adapted to cooperate with oppositely sloping faces of the anvils. The plungers and anvils are both moved toward the plane of operation, when the movement above described takes place, and the plungers engage, from opposite sides, adjacent teeth of a saw held in proper position, and said teeth, backed by the respective anvils, are properly set by the continued pressure exerted through the lever 18, in opposite directions. Thus two teeth are set by one operation and the length of time required to properly set a saw is approximately cut in half. When pressure on the lever 18 is relaxed, the operating blocks 36 and 52 are retracted to normal positions by means of coil springs 65, 66 respectively, connecting said blocks to the arms 28 and 27. The spring 66 is directly connected to an intermediate portion of the curved arm 27; but the spring 65 is connected to a bracket 67 formed on and extending downwardly from one member of the bifurcated portion of the arm 28, and then turned laterally toward the median line of the device.

To adjust the device to operate on saws of varying thickness, the anvils 44, 56 are adjusted vertically in their seats, thus bringing their inclined faces closer to or farther away from the operating edges of the respective plungers. This adjustment is accomplished, as to the anvil 44, by turning the screw 46 to cause the anvil to travel vertically relative to the carrying block 40, and as to the anvil 56 by turning the screw

58 to cause the anvil to travel vertically relative to the operating block 52, the clamping screws 48 and 60 then being set to hold the anvils in their adjusted positions.

To adjust the tool for operation on saws of varying spacing of teeth (coarseness or fineness), the plunger 62 is adjusted laterally by operation of the screw 64, thus moving it toward or away from the plunger 49 in a lateral direction. Also the anvil 44 is adjusted laterally to correspond, by operation of the screw 42, to adjust the carrying block 40 laterally in the operating block 36, and with it the anvil 44.

This double tool greatly reduces the time required to set a given saw and saves turning the saw end for end, as is now commonly done, and putting it through the tool twice, in opposite directions, to set alternate teeth in the same direction.

The roller 22 is made of considerably greater diameter than the roller 21, and consequently its cam groove 38 is correspondingly larger and has greater throw, to compensate for the increased distance of said roller 22 from the lever 18, whereby the travel of both the blocks 36 and 52, with the operating members carried thereby, is substantially equalized, despite the increased length of the arm 28 relative to the arm 27.

I claim as my invention—

1. A double saw set, comprising a frame, a rigid handle on one end thereof, a lever pivoted between its ends on said frame and adapted to cooperate with said handle, a spring acting to press said lever away from said handle, rollers journaled in said frame and formed with cam notches on their opposed faces, arms on said rollers extending toward one end of said lever, toggles flexibly connecting free ends of said arms to the free end of said lever, and saw-treating devices slidably mounted in said frame and movable by action of said cam rollers, said saw-treating devices operating in pairs in opposite directions.

2. A double saw set, comprising a frame, a rigid handle on one end thereof, a lever pivoted between its ends on said frame and adapted to cooperate with said handle, a spring acting to press said lever away from said handle, cam rollers journaled in spaced relation in said frame, arms on said rollers extending toward said lever, toggles flexibly connecting free ends of said arms to the upper end of said lever, anvils arranged in staggered relation in said frame, and plungers arranged opposite said anvils and adapted to cooperate therewith to set adjacent teeth of a saw in opposite directions when said lever is oscillated.

3. A double saw set, comprising a frame, a rigid handle on one end thereof, a lever pivoted between its ends on said frame and adapted to cooperate with said handle, a

spring acting to press said lever away from said handle, cam rollers journaled in spaced relation in said frame, arms on said rollers extending toward said lever, toggles flexibly connecting said arms to the upper end of said lever, anvils arranged in staggered relation in said frame, plungers operable by said cam rollers and arranged opposite said anvils and adapted to cooperate therewith to simultaneously set adjacent teeth of a saw, and springs acting to retract said plungers.

4. A double saw set, comprising a frame, a rigid handle thereon, a lever pivoted on said frame and adapted to cooperate with said handle, a spring acting to press said lever away from said handle, cam rollers journaled in spaced relation in said frame, arms on said rollers extending toward said lever, toggles flexibly connecting said arms to said lever to oppositely rotate said rollers when said lever is oscillated, anvils arranged in staggered relation in said frame, plungers operable by said cam rollers and arranged opposite said anvils and adapted to cooperate therewith to simultaneously set adjacent teeth of a saw, and means for adjusting one of said plungers laterally.

5. A double saw set, comprising a frame, a rigid handle thereon, a lever pivoted on said frame and adapted to cooperate with said handle, a spring acting to press said lever away from said handle, cam rollers journaled in spaced relation in said frame,

connections between said lever and rollers for rotating the latter oppositely when said lever is oscillated, anvils arranged in staggered relation in said frame, plungers operable by said cam rollers, arranged opposite said anvils and adapted to cooperate therewith to simultaneously set adjacent teeth of a saw, means for adjusting said anvils vertically, and means for adjusting one of said anvils and the corresponding plunger laterally.

6. A double saw set, comprising a frame, a rigid handle thereon, a lever pivoted on said frame and adapted to cooperate with said handle, a spring acting to press said lever away from said handle, cam rollers journaled in spaced relation in said frame, connections between said lever and rollers for oscillating the latter oppositely when said lever is oscillated, blocks slidably mounted in said frame between said rollers and operable by the cams thereof toward each other, an anvil carried by each block, screw devices for vertically adjusting said anvils in said blocks, said anvils being arranged in staggered relation, plungers carried by said blocks opposite and adapted to cooperate with said anvils to simultaneously set adjacent teeth of a saw, and screw devices for adjusting one of said anvils and the corresponding plunger laterally in their respective blocks.

ANDREW BERT ANDERSON.
